JOSEPH GASKILL JACKSON, OF BUFFALO, NEW YORK.

FLYING-MACHINE.

1,247,685.

Specification of Letters Patent. Patented Nov. 27, 1917.

Application filed March 29, 1916. Serial No. 87,485.

To all whom it may concern:

Be it known that I, JOSHUA GASKILL JACKSON, a citizen of the United States of America, and a resident of the city of Buffalo, county of Erie, and State of New York, have invented certain new and useful Improvements in Flying-Machines, of which the following is a full, clear, and exact description.

10 My invention relates generally to flying machines, and more particularly to flying machines which raise themselves and maintain their height in the air by presenting a small angle of incidence to the air by means 15 of one or more aeroplanes, and one which is propelled forward either by force of gravity, as in soaring, or by means of a mechanically driven propeller, or otherwise.

The general object of my invention has 20 been to provide a flying machine in which I shall make use of certain principles of physics and the law of gravitation in such a manner that my machine will keep its poise, balance and equilibrium while in the 25 air without the aid of weights, gyroscope, ailerons or other mechanical devices, even in the face of unfavorable weather conditions.

One object has been to provide an aeroplane which will not dive or skid, and to so construct it that if by any chance it should "turn turtle", or assume any other unintended position, while in the air, it will immediately right itself and automatically 35 assume its natural and intended upright position without the aid of any mechanical devices or manually controlled means.

Moreover, my device does not depend 40 upon ailerons for its lateral stability, nor on an elevator for its frontal stability, nor on any other mechanically controlled device or devices, thus enabling the aviator to make any short, sharp or dangerous turn or other maneuver in safety, so far as the equilibrium 45 is concerned and without danger of diving or skidding.

Furthermore, my device is so constructed 50 that when it descends or settles toward the earth, it will move in a perpendicular line without moving in any other direction, thus making it absolutely safe, so far as the equilibrium is concerned.

The above objects and advantages have been accomplished by the device shown in

the accompanying drawings, forming a part 55 of this application. In the drawings:

Figure 1 is a perspective view of my device.

Fig. 2 is a sectional view through the 60 planes, taken on line 2-2 of Fig. 1.

Fig. 3 is a like sectional view taken on line 3-3 of Fig. 1.

My device comprises a tail part 5 and a body part 6. The tail part 5 is composed of three tapering planes, comprising a vertical plane 7 and two diverging planes 8 and 9, which are preferably arranged equidistant around a common line 10 where they are joined together. The upper edge 11 of the vertical plane 7 is inclined at an angle 70 to the edge 12 thereof and meets and joins this edge at the forward end of the tail part 5. Diverging planes 8 and 9 are arranged preferably at the same angle to each other as the angle they assume with the vertical plane 7, and each is tapered from its rear end toward a common point at its front end and is joined to the upper edge of the vertical plane 7 at the line 10. The planes 7, 8 and 9 are preferably braced and tied 80 together by guy ropes 13.

The body part 6 of my machine comprises preferably two body planes 14 and 15, which are joined at their lower edges and meet along the line 16, which is parallel and coincident with the lower edge 12 of the plane 7 of the tail member of my device. Above the planes 14 and 15 is preferably arranged a horizontal plane 17, which is set some distance above the upper edges 18 of the body 90 planes 14 and 15 and preferably supported by posts 19.

20 represents the hood which contains the engine for propelling the machine, and 21 is the cockpit. 22 represents the control levers, contained within the cockpit 21 and within easy reach. 23 is the propeller of my device, which is arranged at the front end of the engine hood 20. My device is provided at its front end with two wheels 24, 100 which are suitably supported and braced beneath the body part 6. A skid 25 is secured between the wheels 24.

Secured to the rear edge of the vertical plane 7 is a downwardly extending skid 26. Secured immediately above the skid 26 is the rudder 27 of my device. This rudder is 105 suitably connected with one of the control

levers 22. Arranged at the upper rear tips of the diverging planes 8 and 9 is the elevator 28 of my device, which is also connected with one of the control levers by any 5 suitable means.

It is well known that any object when pushed or pulled will naturally assume a position in which it offers the least resistance to the force pushing or pulling it. In 10 the case of an aeroplane in the air, gravitation is the dominating force which pulls it toward the earth. In my machine the planes 8, 9, 14 and 15 being turned upwardly at an angle and coming together so as to form a 15 wedge, cause the machine to naturally assume its upright or intended position while in the air, as it offers the least resistance in that position, and it remains in that position because the law of gravitation is continuous. Inasmuch as the line 16, on which 20 the body planes 14 and 15 meet and join, is parallel and coincident with the lower edge of the vertical plane 7, the body planes 14 and 15 offer a different angle of incidence to 25 the air than the planes 8 and 9, and this gives frontal stability and equilibrium, the same as the lateral stability which is secured by the angles formed between the diverging planes 8 and 9 and vertical plane 7. 30 It will thus be seen that my flying machine will always remain in its upright and intended position and its equilibrium assured despite unfavorable weather conditions or other forces which would tend to move it 35 from its intended position.

In making a short turn at high speed with the ordinary aeroplane, it is necessary that the aviator make the inner side of his machine tip, which, though a dangerous operation, 40 somewhat prevents skidding by presenting a larger area of the planes to the air. When making a short turn with my device, it will be seen that the planes bank themselves against the air and present a very 45 large plane surface to resist skidding.

My planes are so proportioned that the surface presented to the air by the vertical plane 7 is equal to the combined projected surfaces presented laterally to the air by 50 either the body plane 14 and diverging plane 8, or body plane 15 and diverging plane 9. By this construction, when making a short turn, these equal surfaces are presented to the air and this prevents the machine from 55 "turning turtle," or assuming any unnatural position while making this turn.

Instead of using but one horizontal plane 17, two or more may be arranged over my flying machine, or the horizontal plane may 60 be dispensed with entirely. If the horizontal plane is removed, the angles between the planes 14 and 15 will be increased so that they will present a greater area to the air and thus make up for the carrying surface 65 face of the horizontal plane 17. These and

other modifications of the details herein shown and described may be made without departing from the spirit of my invention or the scope of the appended claims, and I do not wish to be limited to the exact embodiment herein shown and described. 70

Having thus described my invention, what I claim is:

1. A flying machine comprising a tail portion and a body portion, said tail portion 75 comprising a vertical plane and two diverging planes, said planes being arranged around a common line, and extending substantially throughout the length of the machine and tapering throughout their length from a common point near the front of the machine to the rear thereof, said body portion comprising two body planes which are joined together at their lower edges and disposed about the forward end of said tail portion. 80

2. A flying machine comprising a tail portion and a body portion, said tail portion comprising a vertical plane and two diverging planes, said planes arranged around a common line, said body portion comprising 90 two body planes which are joined together at their lower edges and disposed about the forward end of said tail portion, said body planes meeting and joining in a line which is coincident with the lower edge of said 95 vertical plane, whereby frontal stability and equilibrium are maintained.

3. A flying machine comprising a tail portion and a body portion, said tail portion comprising a vertical plane and two diverging planes, said planes arranged around a common line, said body portion comprising two body planes, said vertical plane having substantially the same area as the combined laterally projected areas of the body 105 plane and the diverging plane on either side of the machine, whereby skidding is prevented and equilibrium is assured.

4. A flying machine comprising a tail portion and a body portion, said tail portion comprising a vertical plane and two diverging planes, said planes arranged around a common line, said body portion comprising two body planes which are joined together at their lower edges and 115 disposed about the forward end of said tail portion, said body planes meeting and joining in a line which is parallel to and coincident with the lower edge of said vertical plane, a rudder secured to the rear end of 120 the vertical plane, an elevator secured to the rearward tips of said diverging planes and means for controlling said rudder and said elevator.

5. A flying machine comprising a tail 125 portion and a body portion, said tail portion comprising a vertical plane and two diverging planes, said planes being arranged around a common line, said body portion comprising two body planes, said 130

vertical plane having substantially the same area as the combined laterally projected areas of the body plane and the diverging plane on either side of the machine, a rudder secured to the rear end of the vertical plane, an elevator secured to the rearward tips of said diverging planes, and means for controlling said rudder and said elevator.

6. A flying machine comprising a tail portion and a body portion, said tail portion comprising a vertical plane and two diverging planes, said planes arranged around a common line, said body portion comprising two body planes, which are joined together at their lower edges and disposed about the forward end of said tail portion, vertically extending posts secured to the upper corners of the body planes, and a horizontal plane disposed above the body planes and secured to the upper ends of the posts, whereby equilibrium is assured by providing a space between the body planes and the horizontal plane.

7. A flying machine comprising a tail portion and a body portion, said tail portion comprising a vertical plane and two diverging planes, said planes arranged around a common line, and tapering from a common point near the front of the machine and extending throughout the length of the machine and to the rear thereof, said body portion comprising two body planes, said vertical plane having substantially the same area as the combined laterally projected areas of the body plane and the diverging plane on either side of the machine,

whereby skidding is prevented and equilibrium is assured.

8. A flying machine comprising a tail portion and a body portion, said tail portion comprising a vertical plane and two diverging planes, said planes arranged around a common line, said body portion comprising two body planes, said vertical plane having substantially the same area as the combined laterally projected areas of the body plane and the diverging plane on either side of the machine, vertically extending posts secured to the upper corners of the body planes, and a horizontal plane disposed above the body planes and secured to the upper ends of the posts.

9. A flying machine comprising a tail portion and a body portion, said tail portion comprising a vertical plane and two diverging planes, said planes being arranged around a common line, said body portion comprising two body planes, said vertical plane having substantially the same area as the combined laterally projected areas of the body plane and the diverging plane on each side of the machine, said body planes being joined together at their lower edges in a line which is coincident with the lower edge of said vertical plane.

In testimony whereof, I have hereunto signed my name in the presence of two subscribing witnesses.

JOSHUA GASKILL JACKSON.
